LOCK NUT FOR CONDUITS AND ELECTRIC FITTINGS

Lawrence M. Curtiss, Mountainside, N.J., assignor to The Thomas & Betts Co., Elizabeth, N.J., a corporation of New Jersey

Filed Aug. 31, 1961, Ser. No. 66,578

Term of patent 14 years

(Cl. D54—9)

Fig. 1

Fig. 2

Fig. 3

Fig. 4

Fig. 5

FIG. 1 is a perspective view of a lock nut for conduits and fittings, showing my new design;

FIG. 2 is a view in elevation of the end shown in FIGURE 1;

FIG. 3 is an elevational view taken from the right of FIGURE 2;

FIG. 4 is a perspective view thereof as seen from opposite end of FIGURE 1; and

FIG. 5 is a sectional view taken on the line 5—5 of FIG. 2.

I claim:

The ornamental design for a lock nut for conduits and electric fittings, as shown.
